(57) **CLAIM**

The ornamental design for a sprinkler head accessory, as
shown and described.

DESCRIPTION

FIG. 1 is a front elevational view of a sprinkler head
accessory showing my new design;

FIG. 2 is a rear elevational thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a perspective view thereof;

FIG. 8 is a cross-sectional view thereof, taken in the direction
of line 8-8 of FIG. 1;

FIG. 9 is a front elevational view of the sprinkler head
accessory and an outer cover of a sprinkler head, wherein the
sprinkler head accessory is in a using position with the outer
cover; and,

FIG. 10 is a cross-sectional view thereof, taken in the
direction of line 10-10 of FIG. 9.

The broken lines shown in FIGS. 1-10 which illustrate the
center area features of the article depict portions of the
sprinkler head accessory that form no part of the claimed
design.

The broken lines shown around the sprinkler head accessory
in FIGS. 9 and 10 depict the environment of an outer cover
that forms no part of the claimed design.

1 Claim, 10 Drawing Sheets
